DISH

Victor J. Bergeron, Hillsborough, Calif.
(20 Cosmo Place, San Francisco, Calif. 94109)

Original design application Feb. 23, 1965, Ser. No. 83,943.
Divided and this application Mar. 2, 1966, Ser. No.
1,243

Term of patent 14 years

(Cl. D44—10)

FIG. 1.

FIG. 2.

FIG. 3.

FIG. 1 is a perspective view of a dish showing my new design;

FIG. 2 is a top plan view thereof, with another dish shown in broken lines and associated therewith for illustrative purposes; and

FIG. 3 is a right side elevational view.

This application is a division of my earlier application Ser. No. D. 83,943, filed Feb. 23, 1965, and now abandoned.

I claim:

The ornamental design for a dish, as shown and described.
